RADIO DIRECTION FINDER

Frans Fransson, Stockholm, Sweden, assignor to
 Aga-Baltic Radio Aktiebolag, Stockholm,
 Sweden, a corporation of Sweden

Application November 24, 1937, Serial No. 176,155
 In Sweden November 26, 1936

6 Claims. (Cl. 250—11)

My invention relates to oscillating radio direction finders, and more particularly to phase shifting means for use in connection therewith.

An oscillating directional radio transmitter generally includes two antenna systems, for instance one directed and one undirected system, and arrangements for repeated shifting of the phase condition of the field of one of the antenna systems in relation to the phase condition of the field of the other antenna system. The phase shifting causes the field characteristic of the antenna systems to oscillate between two different positions, the direction of the so-called beam emitted by the transmitter being determined by the intersections between the field characteristics in one position and the field characteristics in the other position. It is usual to send different signals in different positions of the resultant field characteristics, so that for instance a long signal is sent in one position of the field characteristics alternating with a short signal in the other position. In the direction of the beam the sound is then heard as one uninterrupted signal of constant intensity. In any directions not coinciding with the beam, on the other hand, a short or a long signal of greater intensity is received alternating with a long or short signal, respectively, of lesser intensity.

The function of an oscillating directional radio receiver is analogous to the function of an oscillating directional radio transmitter. Like the oscillating directional radio transmitter, the oscillating directional radio receiver contains two different antenna systems, for instance one directed and one undirected antenna system. During repeated shifting of the phase condition of the current from the two antenna systems and turning of the resultant field characteristics of the antenna systems, the signal from a directional radio transmitter is received. The direction of the beam is recognized by the fact that the signal is received with constant intensity, independently of the phase shifting.

The arrangements for the above mentioned phase shifting are connected to the input terminals to one of the antenna systems of the transmitter or receiver, respectively, for instance the undirected system. It is of great importance that such a phase shifting arrangement should function with very great speed at the moment of phase shifting, so that the current changes its phase without being interrupted for any appreciable time. Repeated interruptions of appreciable duration of the antenna current cause interruptions in the signal even in the direction of

the beam, whereby the determinings of the direction are made more difficult. In addition, the phase shifting arrangements should not result in noticeable interfering sounds occurring upon phase shifting, such as audible clicking or the like.

Phase shifting arrangements of the above mentioned kind are known, which consist of four fixed condenser plates shaped as sectors of a circle and one additional movable condenser plate, arranged to move in a circular path in one direction and at a constant speed along the fixed plates, one of the antenna systems of the direction finding apparatus being connected to the movable plate, and the fixed plates being connected in pairs of two points in the transmitter, having voltages of opposite phase. Phase shifting occurs every time the movable plate passes the space or gap between adjacent fixed plates. In order to obtain signals of different length in different phase positions, the fixed plates have surfaces of different size.

In view of the fact that in the known phase shifting arrangement the movable plate moves one direction at a constant speed, and as this speed must be considerable in order to obtain the quickest possible phase shifting, it is necessary that the surfaces of the fixed plates be very large in order to obtain the desired duration of signals of different phases, which involves certain disadvantages. Fixed condenser plates of different size entails, further, an undesirable capacitive unbalance in those circuits of the transmitter to which the phase shifting arrangement is connected.

The present invention relates to an improvement in the known phase shifting arrangements and consists in the movable plate being given an oscillating movement back and forth over two adjacent fixed plates, or a movement in one direction at a varying speed. For movement of the plate in one direction the speed should be higher during the passage over the space between the fixed plates than during the passage over one, at least, of the fixed plates. With the oscillating movement, as well as with the movement in the same direction at a varying speed, the same speed, or even a higher speed of phase shifting can be obtained than in the phase shifting arrangements previously known, and in addition the fixed plates may be made considerably smaller. Also, all the fixed plates may be of the same size and alternating long and short signal signs may be obtained with movement in the same direction by causing the movable plate to

move at a lower speed when passing, for instance, every other fixed plate than when passing the other plates or the movement of the plate may be caused to take place in steps and to remain stationary during intervals of different lengths before different fixed plates. If the plate has an oscillating movement the same result may be obtained by causing the plate to move through arcs of different amplitude over the fixed plates.

10 The arrangement according to the invention may be modified in such a way that the plate described in the above as being movable is arranged as a fixed plate, whereas the other plates are arranged to be movable. All plates may be arranged to be movable in such a way that the same relative movement desired between the plates is obtained.

Furthermore, the invention is not limited to purely capacitive phase shifting arrangements 20 but may also be applied to inductive phase shifting arrangements, or to commutator phase shifting devices and is not limited to any particular number of fixed or movable plates.

The invention will be described further in the 25 following with reference to the attached drawing that shows one embodiment of the invention.

Fig. 1 is a wiring diagram of an oscillating directional radio transmitter including a phase shifting device according to the present invention;

Fig. 2 is a more or less diagrammatic view of the phase shifting device shown in Fig. 1;

Fig. 3 is a cross-sectional view taken on the line 3—3 of Fig. 2;

Fig. 4 is a diagram showing certain field characteristics;

Fig. 5 is a diagram showing certain other field characteristics;

Fig. 6 is a diagrammatic view of an example 40 of an apparatus suitable for operating the phase shifting device; and

Fig. 7 is a diagrammatic view of a modification 45 of the apparatus shown in Fig. 6.

In Fig. 1 reference character 1 indicates an oscillating circuit included in an oscillating directional radio transmitter, in which circuit the signal oscillations of high frequency occur. To the oscillating circuit 1, a directed antenna system consisting of two similar directional antennae 2 50 and 3 is connected through a goniometer 4 and a coil 5 inductively connected to the oscillating circuit.

The oscillating circuit 1 is grounded at the middle point of the coil 6 and the ends of the 55 coil are connected to an undirected antenna system consisting of an open antenna 7 through a phase shifting arrangement in accordance with the present invention. The phase shifting arrangement which in this case is shown as a capacitance includes four fixed condenser plates 8, 9, 10 and 11, and two movable plates 12 and 13, the latter being connected to each other and to the antenna 7. The fixed plates are all of the same size and are connected in pairs to the opposite ends of the coil 6.

The construction of the phase shifting arrangement is seen more clearly from Figs. 2 and 70 3 which show two sections taken at right angles to each other. The movable plates are secured to a rotatable shaft 14 of a driving device 15 which is arranged to oscillate the shaft 14 and plates 12 and 13 through an angle ν of 90°. The antenna 7 is connected to the movable plates through a capacitive collector, consisting of condenser plates 16 secured to the shaft 14 and of

fixed plates 17 connected with the antenna. Shaft 14 serves as a conductor for connecting plates 12 and 13 to plates 16.

The two ends of the coil 6 carry voltages of opposite phase. The oscillations of the movable plates cause the antenna to be connected alternately to either of these ends, whereby the desired phase shifting of the antenna current is obtained. These phase shifting cause the resultant field characteristic of the antenna systems to oscillate between two different positions, as is shown graphically in Figs. 4 and 5.

In Fig. 4, 18 represents the field characteristic for the undirected antenna system 7 at a certain value of the current through it. Reference character 19 represents the field characteristic for the directed antenna systems 2, 3. The last mentioned field characteristic is of so called figure-8 form. At the phase condition of the fields indicated by the signs + and — a resultant cardioidic field characteristic 20 is obtained.

Upon phase shifting of the current through the undirected antenna system and consequent phase shifting of the field of this system, the resultant field characteristic changes its position. The shape of the field characteristic, however, remains unchanged provided that the current is not changed. In Fig. 5, the curve 20' indicates the position of the resultant field characteristic after the phase shifting with unaltered current. In the same figure the previous position of the field characteristic is indicated by curve 20.

The directions of the beam are determined by the intersections of the resultant field characteristics 20 and 20'. As seen from Fig. 5, the directions indicated by the lines O—x and O—y are displaced by 180° in relation to each other in the case where the current in the undirected antenna system is constant, independently of the phase shifting.

For the purpose of obtaining signals of different duration in different positions of the resultant field characteristic, the driving arrangement 45 for the movable plates of the phase shifting arrangement may be made in such a way that the movable plates will remain in one of their extreme positions for a longer time than in the other extreme position. As a rule, however, it is more desirable to have the movable plates oscillate without any other retarding of the movement in the two extreme positions than that caused by the inertia, etc., of the movable masses, and to make the duration of the signals in the two phase positions unequal by displacing the central points of the fixed plates in relation to the extreme positions of the movable plates, so that the movable plates will move over surfaces of different area on the different fixed plates. In the arrangement shown in Fig. 2 the central points of the fixed plates are displaced in relation to the extreme positions of the movable plates in such a way that the arcs indicated by a have a greater amplitude than the arcs indicated by b . The relation between the duration of the signals in the two phase positions is then determined by the relation between the arc a to the arc b , which relation is adjustable.

In the arrangement described above a very quick phase shifting is obtained, the speed of the movable plates being very high when these plates pass the spaces or gaps between fixed plates. This is because the mass of the movable plates is comparatively small and the driving arrangement 70 is made in such a way that the acceleration of the plates after the reversal of move-

ment in the two extreme positions is comparatively rapid.

An example of a suitable driving arrangement is shown more or less diagrammatically in Fig. 15 is shown more or less diagrammatically in Fig. 6. Reference character 25 designates a rotating disc mounted on a shaft 26 which is driven by a motor 27. The speed of motor 27 may be regulated in any suitable manner, such as by the rheostat 44 included in its circuit. Disc 25 includes two sections 28 and 29 of conducting material separated by insulating material 30. Also mounted on shaft 26 are slip rings 31 and 32 which are electrically connected to sections 28 and 29, respectively.

15 A brush 33 is arranged to bear against the outer periphery of disc 25 and is connected to one terminal of a battery 34 or other source of electrical energy. The other terminal of battery 34 is connected to oppositely disposed electromagnets 35 and 36. Brushes 37 and 38 bear against slip rings 31 and 32, respectively, and are connected to electro-magnets 35 and 36, respectively.

20 A rack 39 is slidably mounted in suitable supports 40 and is provided with an armature element 41 of magnetic material which is disposed so as to be attracted by either of the electromagnets 35 or 36 when the latter are energized. The rack 39 is provided with teeth 42 which mesh with a pinion 43 mounted on the shaft 14 shown, for instance, in Fig. 3.

25 The above described device operates as follows: As disc 25 rotates brush 33 is in contact first with section 28 and then with section 29 thereof. When the brush is in contact, for instance, with section 28, as shown in Fig. 6, the circuit is completed from one terminal of the battery 34 through brush 33, section 28, slip ring 31 and brush 37 to electromagnet 35 and back to the other terminal of the battery through the permanent connection of the electro-magnet therewith. The electro-magnet 35 is thereby energized and armature member 41 is attracted thereto and moves the rack 39 to the left, as viewed in Fig. 6, to the position shown in this figure. This causes rotation of the pinion through the arc ν shown in Fig. 2. When the disc 25 has rotated sufficiently so that brush 33 comes into contact with section 29, the circuit through electro-magnet 35 is interrupted and a similar circuit is established through section 29, slip ring 32 and brush 38 with electro-magnet 36. This causes magnet 36 to be energized and armature element 41 is attracted thereto and causes the rack 39 to move to the right, as viewed in Fig. 6, thereby rotating pinion 43 and shaft 14 back through the arc ν .

30 The speed of motor 27 may be regulated so that the sections 28 and 29, respectively, of the disc 25 pass out of contact with the brush 33 at approximately the instant that armature element 41 reaches the electro-magnet which has just been energized. With such an adjustment of the speed of the motor, rack 39 will oscillate with but a momentary stop at its extreme positions. If it is desired to have the rack stationary for an appreciable length of time in its extreme positions, the speed of the motor may be reduced by means of the rheostat 44 so that the armature element will reach the energized electro-magnet before the respective sections 28 and 29 of the disc have completely passed the brush 33, whereby the armature element will be held in its extreme position against the energized magnet for an ap-

preciable length of time before the other magnet becomes energized.

If it is desired to cause the rack 39 to remain at rest for a greater period in one of its extreme positions than in the other, the disc 25, shown in Fig. 7, may be substituted for the disc 25 in Fig. 6. In the disc 25', the sections 28' and 29' are unequal, section 28' being the larger, whereby brush 33 remains in contact with the section 28' for a greater length of time than it remains in contact with section 29'. This in turn causes electro-magnet 35 to be energized for a greater length of time than electro-magnet 36 and consequently the armature element 41 remains in its left-hand position, as viewed in Fig. 6, for a longer period than it remains in the opposite position.

35 As previously mentioned, the condenser plates included in the phase shifting arrangement may be replaced by commutators, or by devices known per se for inductive transmission of voltage, and the arrangements also may be modified in various other ways without deviating from the principle of the invention. In the embodiment shown, the condenser plates 10, 11 and 13 may be omitted, in which case the phase shifting arrangement will consist of a movable condenser plate connected to the antenna 1 and of two fixed condenser plates connected to points of the circuit which carry voltages of opposite phase. The antenna need not be connected directly to the phase shifting arrangement, but may be connected to this through coupling elements of any suitable kind.

The scope of my invention is not to be limited by the above description, given by way of example only, but is to be determined by the appended claims viewed in the light of the prior art.

40 What is claimed:

1. In an oscillating radio direction finder, an oscillating circuit, a directed antenna coupled to said circuit, an undirected antenna coupled to said circuit, and means for shifting the phase of the voltage applied to one of said antennae with respect to the phase of the voltage applied to the other antenna, including impedance elements connected to points of opposite phase in said circuit, an impedance element connected to said one of said antennae, and means for moving the last mentioned element with respect to the first mentioned elements at periodically varying speed.

45 2. In an oscillating radio direction finder, an oscillating circuit, a directed antenna coupled to said circuit, an undirected antenna coupled to said circuit, and means for shifting the phase of the voltage applied to one of said antennae with respect to the phase of the voltage applied to the other antenna, including impedance elements connected to points of opposite phase in said circuit, said elements being spaced with a gap therebetween, an impedance element connected to said one of said antennae, and means for moving the last mentioned element with respect to the first mentioned elements at a speed varying so that said last mentioned element passes said gap at a higher speed than the average speed at which it passes the first mentioned elements.

50 3. In an oscillating radio direction finder, an oscillating circuit, a directed antenna coupled to said circuit, an undirected antenna coupled to said circuit, and means for shifting the phase of the voltage applied to one of said antennae with respect to the phase of the voltage applied to the other antenna, including impedance elements connected to points of opposite phase in said cir-

- cuit, an impedance element connected to said one of said antennae, and means for moving the last mentioned element back and forth opposite to the first mentioned elements.
5. 4. In an oscillating radio direction finder, an oscillating circuit, a directed antenna coupled to said circuit, an undirected antenna coupled to said circuit, and means for shifting the phase of the voltage applied to one of said antennae 10 with respect to the phase of the voltage applied to the other antenna, including impedance elements connected to points of opposite phase in said circuit, an impedance element connected to said one of said antennae, and means for moving the last mentioned element back and forth opposite the first mentioned elements through a path of movement the extent of which is greater than opposite one of said first mentioned elements than opposite the other of said first mentioned 20 elements.
5. In an oscillating radio direction finder, an oscillating circuit, a directed antenna coupled to said circuit, an undirected antenna coupled to said circuit, and means for shifting the phase of the voltage applied to one of said antennae with respect to the phase of the voltage applied to the other antenna, including impedance elements connected to points of opposite phase in said circuit, an impedance element connected to said one of said antennae, and means for moving the last mentioned element relative to the first mentioned 10 element and for stopping said last mentioned element for periods of different duration opposite different of said first mentioned elements.
6. Device as set forth in claim 1 including a fixed capacity condenser between said one of said antennae and the movable element, said condenser including a stationary plate connected to said one of said antennae and a movable plate connected to and movable with said movable element.

FRANS FRANSSON.

20

oscillating circuit, a directed antenna coupled to said circuit, an undirected antenna coupled to said circuit, and means for shifting the phase of the voltage applied to one of said antennae with respect to the phase of the voltage applied to the other antenna, including impedance elements connected to points of opposite phase in said circuit, an impedance element connected to said one of said antennae, and means for moving the last mentioned element relative to the first mentioned 10 element and for stopping said last mentioned element for periods of different duration opposite different of said first mentioned elements.

6. Device as set forth in claim 1 including a fixed capacity condenser between said one of said antennae and the movable element, said condenser including a stationary plate connected to said one of said antennae and a movable plate connected to and movable with said movable element.
